UNITED STATES PATENT OFFICE.

GEORGE H. CLEVELAND, OF CAMDEN, MAINE.

SHIRT.

SPECIFICATION forming part of Letters Patent No. 286,781, dated October 16, 1883.

Application filed August 28, 1883. (No model.)

To all whom it may concern:

Be it known that I, GEORGE H. CLEVELAND, of Camden, in the county of Knox and State of Maine, have invented a new and useful Improvement in Shirts; and I do hereby declare that the following is a full, clear, and exact description of the same.

My invention relates to shirts, and is more especially designed for outside woolen shirts, 10 but is adapted to shirts of any material and style. The object of my invention is to provide a shirt with an entire or closed back and front, adapted to be used either with or without a collar permanently attached.

15 My invention consists of a special construction of the shirt, as hereinafter explained, whereby the back and front are both closed and the opening on the shoulder and back is closed by a re-enforce or flap formed by a separate piece.

20 In the accompanying drawings, Figure 1 is a front view of my improved shirt. Fig. 2 is a view of the flap detached. Fig. 3 is a back view of the shirt. Fig. 4 is a front view, and 25 Fig. 5 a back view of the shirt without a collar.

25 In the drawings, the front A of the shirt is formed in the usual manner of making whole-front shirts, and has a single button or 30 stud at the throat. It may be ornamented in any desired manner by cord, to imitate a laced front, as is common in woolen "bicycle-shirts;" or it may be provided with studs, buttons, plaiting, or any other ornament suited 35 to the material of the shirt or required by the fancy of the wearer. The back B is also 40 made and fitted to the shirt in the ordinary manner—that is to say, connected to the front on the shoulders—except that it is cut away 45 from the neck downward on the line $x y x$ to 50 form a triangular opening, substantially as shown at C. Outside of this I attach a flap, 55 D, stitched, preferably, to the shirt on a line, $z z$, and on the shoulder of 12 1, and a short 2 2, and on the shoulder from sleeve-seam to 45 distance on the shoulder from sleeve-seam toward the neck, as shown at 1 12, Figs. 1 and 4. The upper edge of the body, which may 50 have any desired ornamental stitching, extends across in front of the neck, over the shoulders, and down the back on the line $x y$ z . The flap, being stitched in the manner 55 shown, may be thrown back, and thus the opening enlarged to admit the head of the wearer; but when the garment is on and the flap is brought forward and fastened in place

it covers the opening and overlaps it on both sides around the neck. To the edge 4 4 of this flap I may attach a collar, E, with bands in front and button-holes 5 5 to secure it to the button or stud 6, this single button or 60 stud holding the whole flap secure. Thus the back of the wearer is covered, no buttoning is required in front, and there is no seam to open on the shoulders. In fact, the overlap of the re-enforce completely covers the 65 whole of the back and shoulders and makes a complete upper garment.

The flap D may be made of the same continuous piece as the body of the shirt, and the re-enforce be put in underneath, connecting with the main parts in the same manner as described in connection with the flaps.

In case the shirt be of that class in which a detachable collar is desirable, I omit the collar E and work button-holes at the points 75 7 7. A collar may be buttoned on to the front and rear buttons or studs, and the buttons for the holes 7 7 may be set at any desired point without disturbing the alignment of the collar-buttons; but when a permanently-attached 80 collar is used only one button or stud is required, and there is no opening on the shoulders, and the whole garment fits closely about the neck of the wearer. The collarless form is very well adapted to that class of woolen 85 shirts designed to be used with detachable linen bosoms and collars, and either form is especially fitted for "bicyclists" or others who may desire to wear the shirts without coat or vest.

90 I claim—

1. A shirt having a closed front, a back cut away from the neck to form the opening C, and a flap, D, connected to the body and covering the opening, substantially as described.

2. A shirt having a closed front, a back connected to the front on the shoulders, and away from the neck downward to form an opening, substantially as shown at C, in combination with a flap, D, covering the opening, and having a collar, E, adapted to be connected to the button or stud at the throat, as and for the purpose set forth.

95 In testimony whereof I have signed my name to this specification in the presence of two subscribing witnesses.

Witnesses: GEORGE H. CLEVELAND.

GEORGE BURD,
C. F. GOULD.
